UNITED STATES PATENT OFFICE.

CHARLES B. THOMPSON, OF ST. CATHARINES, ONTARIO, CANADA.

BOBBIN-WINDER.

SPECIFICATION forming part of Letters Patent No. 245,890, dated August 16, 1881.

Application filed January 20, 1881. (Model.)

To all whom it may concern:

Be it known that I, CHARLES BROWN THOMPSON, of St. Catharines, in the county of Lincoln, in the Province of Ontario, Dominion of Canada, have invented certain new and useful Improvements in Bobbin-Winders for Shuttle Sewing-Machines; and I do hereby declare that the following is a full, clear, and exact description of the construction and operation of the same.

The improvement relates to the construction of the presser-pad arranged alongside of the bobbin; also, to an adjustable thread-guide; and, finally, to a spring tension device, in connection with the several operative parts of the apparatus, as hereinafter fully described, and particularly pointed out in the claims.

By reference to the drawings forming part of this specification it will be seen that Figure 1 represents a front view of the device. Fig. 2 is a detached view of the under side of the thread-controller. Fig. 3 is a vertical section of the same. Fig. 4 is the tension on the upper back part of the frame. Fig. 5 is the end 25 of bobbin, showing the slot therein. Fig. 6 is the end of the spindle, showing projections to fit into the slot of bobbin. Fig. 7 represents a portion of the frame with a modified form of screw through which the thread passes, said figure also illustrating a modified construction of bearing or support for one end of the bobbin.

A is a metal frame of any form, preferably of the shape and configuration shown.

The presser-pad and thread-controller which I have devised is composed of two parts, one of which is the presser-pad plate B, and the other the shank B', to which said plate is adjustably secured by means of a screw, e, passing through a slot in the plate. The shank is 35 formed with a hole, through which a pin, f, passes in order to hinge the screw to the frame A. The front plate, B, is curved, as at b', on its front edge, and provided with projecting tips b² at each end of said curved edge. The shank B' of the presser-pad is set in a recess, g, in the frame A, and hinged by the pin f, and is held against or separate from the bobbin by means of a flat spring, g', secured to the rear side of the frame A, a section of which is 45 shown at Fig. 3. The object of making the

presser-pad in two parts is that the front curve of the plate B may be nicely adjusted by means of the screw e for the laying on of the thread evenly, layer on layer, on the bobbin.

C is a screw entering the small end of the frame A above the bobbin, in which is cut a vertical slot terminating in a guide-eye, c, for the thread to pass through on its way from the spool to the bobbin. By slightly turning the screw the guide-eye c in the same is adjusted to 55 guide the thread from the spool at a proper distance from and in a proper direction to the bobbin while being wound, it being obvious that if the screw is turned partly round from the position shown in Fig. 1 the length of 60 thread between the guide-eye and the bobbin will be increased, and also that the line of 65 thread will be directed from the guide-eye to the bobbin, either to the right or to the left of the line of thread represented in said figure, 70 according to the direction in which the screw C is turned.

Instead of forming the screw with the eye c, it may be simply provided with a transverse slot or channel in its head.

D is the tension device, attached to the upper back part of the frame, for producing a slight draft or tension for steadyng the thread in its passage from the spool to the bobbin. This tension device consists of a disk supported on 75 a screw that is secured in the frame A, a spring, a', being arranged upon said screw, between its head and the disk, whereby a spring tension device is produced.

E is the driving-spindle, passing through an 80 opening in the arm of the device. It is surrounded with a spiral spring, j, which adjusts it to the bobbin.

b b are the projections on the inner end of the said spindle, to correspond with and enter 85 the slot a in the bobbin to connect them. Motion is given to the bobbin and spindle by means of a rubber wheel on the end of said spindle, receiving its motion from the wheel of a sewing-machine when it is made to impinge against it.

G is a short support at the other end of the bobbin, which support can be adjusted by a small thumb-screw, k; or the short center or support G can be a screw fitted into the bear- 90

ing, which will be screw-threaded internally, so that the center or support can be adjusted by simply turning the same.

In Fig. 7 the screw C is simply provided with a transverse channel, c, which can be employed in lieu of the eye shown in Fig. 1; also, instead of employing the set-screw k, the adjustable support can be screw-threaded and arranged to work in a screw-threaded bearing, as indicated in said Fig. 7.

It will be observed that I do not claim the presser-pad alone, for it has long been used for various purposes; nor do I claim the arc or segment edge thread-controller alone, for it has been used for various purposes; but

I do claim as my invention—

1. The combination, with the frame and the bobbin-supports in a bobbin-winder, of the presser-pad consisting of a shank portion hinged to the frame and subjected to spring-

pressure, and the presser-pad plate B, adjustably secured to the said hinged shank, substantially as and for the purpose described.

2. The combination, with the main frame in a bobbin-winder, of the screw C, provided with a thread-guide, and adapted to be turned to vary the length of thread between its guide and the bobbin, and also to vary the position of the line of thread between the two, substantially as described.

3. The combination, with the frame A, of the bobbin-supports, the screw C, and the spring tension device D, substantially as described.

Dated at Hamilton, Ontario, Canada, this 15th day of December, A. D. 1880.

CHARLES BROWN THOMPSON.

In presence of—

WM. BRUCE,

CHARLES TAYLOR.
